Term of patent 14 years

(Cl. D15—1)

FIG. 2

FIG. 3

FIG. 1

FIGURE 1 is a front perspective view of a chair showing my design;

FIGURE 2 is a view on an enlarged scale showing the front of the webbing in greater detail; and

FIGURE 3 is an underneath view thereof.

The dominant features of my design reside in the portions shown in full lines on the drawing characterized by a plurality of warp strands in a side-by-side relationship interwoven with wider weft strands, all as shown.

I claim:

The ornamental design for a chair or similar article, substantially as shown and described.
